HEAT-INTERCHANGE MEANS

Charles Adolphe Hubert, Strasbourg, France

Application May 12, 1937, Serial No. 142,209
In France May 20, 1936

3 Claims. (CL 257—248)

This invention has for its object to provide heat-interchange means applicable in all cases where an interchange of heat between liquid and/or gaseous fluids has to take place. This 5 heat-interchange means is in known manner constructed in such a way as to provide for a large interchange surface and yet only necessitates a relatively small volume, that is to say what may be termed its specific interchange power is relatively high.

Heat-interchange means of this kind generally comprise between two single-part or compound front walls a set of parallel tubes passing through plate-like radiator elements. According to the 15 invention these elements are spaced apart by distance pieces of flat iron extending for the whole of the height or/and the width of the interchange means, in such a way as thus to form flow passages of substantially constant section 20 throughout their length.

The attached drawings represent, by way of example, embodiments of heat-interchange means constructed according to the invention, and in which:—

25 Fig. 1 is an elevation partially in section of a first embodiment.

Fig. 2 is a partial plan view of Fig. 1.

Fig. 3 is a combined front face (with covers omitted) and transverse section view of Fig. 1.

30 Fig. 4 represents in two transverse sections, and Fig. 5 in partial plan, a heat-interchange means having its distance pieces arranged alternately in two directions, mutually at right angles.

Fig. 6 shows another embodiment in which the 35 distance pieces are extending over sets of two parallel tubes.

In Figs. 1 to 3, 1 designates the two structures including the front and rear walls of the heat-interchange means, 2 the tubes extending between these structures and connected thereto by their ends, 3 the plate elements constituting the main operative part of the heat-interchange surface and 4 the distance pieces formed by flat iron bars to maintain the separation of the plate elements.

45 The fixing of the tube ends in the two structures 1 can be effected in various ways, and it is advantageous to arrange these structures in such a way that connecting chambers 5 are maintained to connect two successive tubes together, these chambers permitting, moreover, easy access from the exterior to the orifices of the tubes, for example, for the purpose of cleaning, repairs and otherwise. Thus, for example, in Fig. 1, the 50 chamber 5, of cylindrical shape, is closed by a

single conical plug 7, the stem 8 of which passes through a cap 9 covering the chamber externally and held in place by a nut 10 on the stem. By removing the cap and the plug, access can be obtained to the two tubes 2 opening into the 5 chamber 5.

This method of making the tubes communicate with one another is applicable not only when single-part front and rear structures are employed, but also if these structures are formed 10 by the juxtaposition or the superposition of blocks connecting between themselves a vertical or horizontal row of tubes or again two tubes only.

The arrangement described also lends itself to the construction of heat-interchange means having an exterior in the form of a case completely closed on all sides; it is sufficient, for this purpose, to close, by sheet-metal walls extending from the front structure to the rear structure, the sides, top and bottom of the apparatus. This 20 would permit of causing a liquid fluid to pass in the spaces surrounding the tubular system.

Finally, by making the arrangement of the distance pieces 4 alternate, as represented in Figs. 4 and 5, in such a way that they are arranged in 25 two mutually perpendicular directions from one plate 3 to the next, there will be obtained two channel systems independent the one from the other, the channels *x* of one proceeding from bottom to top and those of the other from left to 30 right. This will permit the interchange of heat between a number of fluids greater than two; thus it would be possible for example, to cause smoke gases to pass in the vertical channels *y* and water to be heated in the tubes 2. In any 35 case, the exterior distance pieces form obturators opposing the entry of fluid which must not pass through the channels which they define.

Whilst in all embodiments as now described the flat iron bars forming the distance pieces between the radiator plates extend but over one row of tubes, it would also, in some cases, be of utility in having them extended over two or more adjacent rows as shown in Fig. 6 in which said flat iron bars 4 between the plates extend over two 45 adjacent rows of tubes 2.

I claim:

1. In a heat-interchange means for fluids of any nature, comprising two front structures, a set of intercommunicating parallel tubes extending between said structures, plate-like radiator elements on the tubes kept spaced apart the one from the other by distance pieces, said distance pieces being flat iron bars traversed by the tubes and extending over the radiator elements in such

a way as to form flow passages of substantially constant transverse section throughout their length.

2. In a heat-interchange means for fluids of any nature comprising two front structures, a set of intercommunicating parallel tubes extending between said structures and plate like radiator elements on the tubes kept spaced apart, the one from the other by distance pieces, said distance pieces being flat iron bars traversed by the tubes and extending alternately for the whole of the height and width of the radiator elements in such a way as to form flow passages of substantially constant transverse section throughout their length and crossing each other perpendicularly.

3. In a heat-interchange means for fluids of any nature comprising two front structures, a set of intercommunicating parallel tubes extending between the front structures, the communication between the tubes taking place through chambers arranged in said front structures, removable covers for obturating the chambers, plate-like radiator elements on the tubes kept spaced apart, the one from the other by distance pieces said distance pieces being flat iron bars traversed by the tubes and extending over the radiator elements in such a way as to form flow passages of substantially constant transverse section throughout their length.

CHARLES ADOLPHE HUBERT. 15
